UNITED STATES PATENT OFFICE

RAY GREENLEAF, OF NEW YORK, N. Y.

COLOR SYSTEM FOR DISGUIISING OBJECTS

Application filed September 8, 1928. Serial No. 304,713.

My invention relates to means for disguising unsightly objects, and structures exposed to public view, and consists of an arrangement of special colors in a definite relation to each other displayed upon the surface of an object that otherwise may be unsightly or ugly in appearance, the effect of which is to make it less conspicuous, or camouflage it to such extent as to cause it to be of little or no offense to the public eye.

My invention is designed especially for use in treating stationary objects in public places, such for instance as storehouses, gas holders, and the like. It is commonly known that such structures, and particularly gas holders, greatly disfigure public places. One or more are present in almost every community and some of them are of huge size and always obtrusive and disfigure the surroundings for those living in the neighborhood or passing by, and because of their objectionable appearance, depreciate the value of adjacent property.

Referring to the drawings, Fig. 1 is a diagram of one unit of my invention. Fig. 2 is a diagram of a plurality of units arranged in the requisite relation to each other to produce the desired effect. Fig. 3 is a perspective view of a section of a gas holder displaying my invention. Similar numerals indicate corresponding parts in the several figures of the drawing.

The unit shown in Fig. 1 illustrates three divisions of approximately equal dimensions each bearing a distinct hue or color. Division 4 is a reddish purple hue, division 5 is blue and division 6 is a greenish blue.

In Fig. 2 the units are assembled in a chart showing them related so that each division is located one step below the corresponding division in the adjacent unit on the left.

In Fig. 3 I have shown three columns, 7, 8, and 9, of the units, displayed in the order and relation shown in Fig. 2, except that the first division of column 8 bears the hue of division 6 of the unit, namely greenish blue, and the first and second divisions of column 9 bear the hues of divisions 5 and 6 of the unit Fig. 1, namely, blue and greenish blue, respectively. It is obvious that this exception

becomes necessary if the surface of the structure is to be completely covered, for the reason that my arrangement of the hues otherwise leaves the top space in column 8, and the two top spaces in column 9 blank. While it is not necessary to color these blank spaces, I prefer to do so and thereby completely cover the structure with the colors or hues substantially in the order described.

Assuming the invention to be applied to a large cylindrical structure like a gas holder, the colors would be applied to so much of the surface as is exposed to public view and in sections corresponding to the columns in Fig. 2 and in the same order and relation as there shown, and described hereinbefore.

The areas of the sections corresponding with the columns, shown in Fig. 2, would depend somewhat upon the size of the gas holder or structure. I have found by experience that a good general rule to follow is to divide the surface into three equal areas 10, 11, and 12 by two imaginary horizontal lines and to divide each of these areas by imaginary vertical lines from ten to thirty feet apart. The several columns thus formed corresponding to the columns of colors in Fig. 2 would again be divided by imaginary horizontal lines from two to five feet apart so that the area of any one of the numbered sections in Fig. 2 would be from two to five feet high by from ten to thirty feet wide. These directions are to be taken for a general guide only and are not essential to my invention for the reason that units of any size, arranged in the order described, will to a greater or less degree accomplish the object of my invention.

A large structure, however ugly in appearance, having my invention applied to it becomes so disguised that it will seldom be noticed by passers-by and even may be overlooked when seeking to locate it.

I have discovered that in clear weather the desired result is attained when using an area about thirty feet long and three feet high for each of my color units. When this area is used the colors will blend together when viewed from a minimum distance of about one mile.

It is obvious that the illumination upon the object will vary to some extent the distance from which the desired effect will be attained, but the dimensions suggested will be a sufficient guide to enable one to apply the system under varying conditions.

What I claim and desire to secure by Letters Patent is:

1. A color system for disguising objects comprising a plurality of units, each unit having three divisions of substantially equal area bearing the colors reddish purple, blue, and greenish blue, respectively, arranged in the order named, said units being located side by side and in contact, with the colors in the same sequence, and each color division being located next to a different color division in the adjacent unit.
2. A color system for disguising objects comprising a plurality of units, each unit having three divisions of substantially equal area bearing the colors reddish purple, blue and greenish blue, respectively, arranged in the order named, said units being located side by side and in contact, with the colors in the same sequence, and the first named color division in a given unit being located next to the second color division in the adjacent unit on the left.
3. A structure having applied to the surface thereof a plurality of units of color, each unit having three divisions of substantially equal area bearing the colors reddish purple, blue and greenish blue, respectively, arranged in the order named, said units being located side by side and in contact, with the colors in the same sequence, and each color division being located next to a different color division in the adjacent unit.
4. A structure having applied to the surface thereof a plurality of units of color, each unit having three divisions of substantially equal area bearing the colors reddish purple, blue and greenish blue, respectively, arranged in the order named, said units being located side by side and in contact, with the colors in the same sequence, and the first named color division in a given unit being located next to the second color division in the adjacent unit to the left.

In testimony whereof I have hereunto set my hand this 24th day of August, 1928.

RAY GREENLEAF.
